VALVE FOR CARBURETORS

Paul P. Bauerschmid, Meriden, Conn., assignor
to Chandler-Evans Corporation, a corporation
of Delaware

Application August 14, 1941, Serial No. 406,789

14 Claims. (Cl. 251—12)

My invention relates to valves for carburetors. It has among its objects to provide an improved throttle mechanism for carburetors and, more particularly, such a throttle mechanism especially adapted to use in connection with airplane carburetors. A further object of my invention is to provide such a throttle mechanism adapted to use in such a carburetor having large rectangular air passage means leading to the engine and adapted to control the air flow therethrough to the engine in an improved manner. Other objects of my invention are to provide such a throttle mechanism having throttle members of an improved construction and journaled in an improved manner at their opposite ends and intermediate their ends, and also having improved sealing means for the throttle members at the extremities thereof and adjacent the intermediate journal thereof. Other objects and advantages of my improvements will hereinafter more fully appear.

In the accompanying drawing, I have shown for purposes of illustration one embodiment which my invention may assume in practice.

In this drawing:

Figure 1 is an end elevation, partially in section, of a carburetor equipped with my improvement;

Fig. 2 is an enlarged sectional view on line 2—2 of Figure 1;

Fig. 3 is an enlarged detail sectional view on line 3—3 of Figure 1;

Fig. 4 is a detail, partially in section, showing one of the end seals and its associated journal mechanism, and

Fig. 5 is a section on line 5—5 of Figure 1 on a somewhat reduced scale showing the throttle members in the fully open position shown in Figure 1.

In this illustrative construction, I have shown my improvements embodied in a carburetor casing 1 having a rectangular air flow passage 2 therethrough; my improved throttle members, generally indicated at 3, being adapted to control the air flow through said passage and journaled at their ends in the casing 1 and intermediate their ends in a transverse septum 4 in the passage 2 between the fuel inlet or fuel bar 5 and suitable rectangular Venturi mechanism, generally indicated at 6, and said throttle members 3 being operated from any suitable operating member 7 through usual cooperating meshing geared sectors 8.

Referring more particularly to the throttle members 3, it will be noted that each of the same comprises a shaft 9 carrying at longitudinally

spaced points thereon elongated generally elliptical hollow members 10 suitably fixed as by rivets 11 to the shaft 9 and tapering therefrom to parallel edge portions 12 to provide generally elliptical hollow throttle members. As shown, each of these members 10 abuts at its opposite end an annular member or disc 13 and has each edge 12 of the throttle member extended slightly beyond the periphery of this disc. Of these discs 13, the discs at the inner ends of the throttle members 10 fit snugly on the shaft 9 and abut opposite sides of a middle bearing sleeve 14 fixed to this shaft as by a rivet 15. Herein, this sleeve 14 is journaled in split bushings 16 held together by a spring ring 17 and mounted in a transverse aperture 18 in the transverse septum 4. The discs 13 at the outer ends of the throttle members, on the other hand, are carried on reduced portions 19 on the shaft 9 and abut ball bearings 20 carried on a smaller bearing sleeve 21 on an adjacent reduced portion 22 of the shaft.

Operatively associated with each end of each throttle member, and, more particularly, with the disc 13 at each end thereof, is improved sealing means. Herein, these sealing means at the inner ends of the throttle members include peripheral flanges 23 on opposite sides of the split bearing members 16, receiving and providing journals for the peripheries of the discs 13. Similarly, at their outer ends, the throttle members have their discs 13 journaled in peripheral flanges 24 on cup members 25 and 26 receiving the ball bearings 20 and suitably fixed to suitable end plates 27 and 28 attached to the casing 1. Herein, the cup 25, which is adjacent the gears 8, is longer than the cup 26 and has a plurality of oppositely disposed loading springs 29 between the end wall of the same and the ball bearing 20, a like construction being provided on the right hand ends of both shafts 9. The cup 26, on the other hand, snugly fits against the end of the bearing 20 and has a single loading spring 30 carried on a collar 31 suitably fixed to the shaft and positioning the bearing 20; this spring herein acting against a suitable abutment face 32 on the end plate 28 and a suitable washer 33 and packing seal 34 between the same and the end of the cup. At this end of the shaft 9, which also carries the operating member 7, a packing gland 35 is also provided around a reduced portion on the shaft 9 and held in sealing position by a coiled spring 36 acting between the same and an abutment 37 fixed to an adjacent portion of the shaft 9. The like end of the other shaft 9, while provided with a like cup 26, has no seal or springs, as shown in Figure 3.

In the use of the throttle members, it will be apparent that as the same are rotated by their operating member 7 and gears 8, the shafts 9 will rotate in their ball bearings at the opposite ends of the shafts, while the sleeves 14 provide journals intermediate the ends of the shafts. Further, the discs 13 provide sealing means at opposite ends of each throttle member 10, these discs rotating inside their cooperating peripheral flanges 23 and 24 in such manner as to prevent the passage of air through the throttles at either end of either throttle member 10. Attention is also directed to the fact that the sealing relation between the discs and annular flanges is maintained by the loading springs 28, these double loaded springs acting to maintain the desired sealing relation, despite longitudinal expansion or contraction of the parts. Attention is also directed to the fact that these springs further act to take up wear at the opposite ends of the shaft and thereby maintain the desired sealing relation.

As a result of my improved construction, effective seals are provided at the ends of the throttle members in such manner that with the seals previously provided along the outer edges of the throttle members, any leakage along either the ends or sides of the throttle member is effectually prevented. At the same time, it is made possible to provide the throttle members in the form of light, hollow bars and also to journal the same, not only at their ends, but between their ends in such manner as to insure proper operation of the same under all conditions. Attention is also directed to the facility with which the throttle members may be assembled, it being possible, after the assembly of one end plate, as, for example, the end plate 27, to slip the throttle bar assembly into the operative position illustrated in Figure 2 and thereafter to insert the cup 26 and spring 32, after which the end plate 28 may be secured in position. These and other advantages of my improved construction will, however, be clearly apparent to those skilled in the art.

While I have herein specifically described one embodiment which my invention may assume in practice, it will be understood that the same has been shown for purposes of illustration, and that the invention may be modified and embodied in other forms without departing from its spirit or the scope of the appended claims.

What I claim as new and desire to secure by Letters Patent is:

1. In a carburetor, a casing having air passage means, a throttle member in said passage means and journaled in said casing, and sealing means for the opposite ends of said member, each of said sealing means including cooperating cup and cup closure members, said cups being fixed to said casing and surrounding said journals and said cup closures being rotatable with said member and axially movable in said cups.

2. In a carburetor, a casing having air passage means, a throttle member in said air passage means and journaled in said casing, sealing means for the opposite ends of said member having cooperating elements respectively carried on the walls of said air passage means surrounding the member journals therein and on said throttle member around the axis thereof, and spring means acting on one element of said sealing means for maintaining said sealing means in sealing relation.

3. In a carburetor, a casing having air passage

means, a throttle member in said air passage means and journaled in said casing, cooperating sealing elements for one end of said member, one carried by said casing and surrounding the journal therein and the other by said member and surrounding the axis thereof, and oppositely acting spring means for maintaining said sealing elements in sealing relation irrespective of relative longitudinal movement of the parts due to temperature variations.

4. A throttle member for carburetors comprising a shaft, a journal carried on said shaft intermediate the ends thereof, discs spaced longitudinally on said shaft at opposite ends thereof and at opposite ends of said journal, and generally rectangular throttle members enclosing the portions of the opposite ends of said shaft between the pairs of discs on opposite sides of said journal.
5. A throttle member for carburetors comprising a shaft, a journal carried on said shaft intermediate the ends thereof, discs spaced longitudinally on said shaft at opposite ends thereof and at opposite ends of said journal, generally rectangular throttle members enclosing the portions of the opposite ends of said shaft between the pairs of discs on opposite sides of said journal, and sealing means between said journal and the discs adjacent the latter.
6. A throttle member for carburetors comprising a shaft, discs spaced longitudinally on said shaft, a generally rectangular throttle member enclosing said shaft between said discs, and sealing means cooperating with said discs at opposite ends of said throttle member and having open ends in which said discs are axially movable.
7. A throttle member for carburetors comprising a shaft, discs spaced longitudinally on said shaft, a generally rectangular throttle member enclosing said shaft between said discs, bearings at opposite ends of said shaft adjacent said discs, and sealing members enclosing said bearings and said discs and having the latter axially movable in said sealing members.
8. A throttle for carburetors including a throttle shaft, longitudinally spaced generally rectangular throttle members thereon, an intermediate journal member between said throttle members, end journal means at opposite ends of said throttle shaft, discs at opposite ends of each throttle member and carried on said shaft between said throttle members and said intermediate and end journal means, and sealing means cooperating with said discs including flanged cups housing said end journal means and oppositely directed flanges on said intermediate journal means.
9. A throttle for carburetors including a throttle shaft, longitudinally spaced generally rectangular throttle members thereon, journal means between said throttle members comprising a journal sleeve enclosing said shaft between the opposite ends of said throttle members, discs between the opposite ends of said throttle members and said sleeve, and cooperating split journal members enclosing said sleeve, and spring means holding said split journal members in said enclosing relation.
10. A throttle for carburetors including a throttle shaft, longitudinally spaced generally rectangular throttle members thereon, journal means between said throttle members comprising a journal sleeve enclosing said shaft between said throttle members, discs between the opposite ends of said throttle members and said sleeve,

cooperating split journal members enclosing said sleeve, spring means holding said split journal members in said enclosing relation, and sealing flanges on opposite ends of said split journal members cooperating with said discs.

11. In a device such as described, a casing having a passage with a planar limiting wall, a shaft journaled in said wall in perpendicular relation thereto and disposed in the passage, a flap valve having a body fixed to the shaft and including in its structure a sealing element in the form of a disk at the end of the valve body adjacent said planar wall, and a sealing element to cooperate with said disk mounted in the planar wall, said sealing elements being capable of relative axial movement.

12. In a carburetor, a casing having an air passage therethrough, a throttle member in said air passage journaled in said casing, and sealing means for an end of said throttle member including cooperating cup and cup-closure elements, one of said elements being carried by the casing and surrounding the journal therein, and the

other being carried by the throttle member and surrounding the axis thereof and axially movable with respect to said first sealing element.

13. In a device such as described, a casing having a passage with a planar limiting wall, a shaft having an end journaled in said wall, a flap valve carried by said shaft and provided with sealing means constituted by an end wall in close proximity to the planar wall, and additional sealing means in the planar wall, said two sealing means being relatively axially movable.

14. In a device such as described, a casing having a passage with a planar wall, a shaft perpendicular to said wall and journaled therein, a flap valve on said shaft having an end wall in close proximity to the planar wall, and a sealing member receiving the end wall of the valve located in a recess in the wall around the shaft, said shaft and said sealing member being relatively axially movable, and means exerting axial pressure on one of said last-named elements.

PAUL P. BAUERNSCHMID.
